AGGREGATING AND DISPLAYING DEVICE,
PARTICULARLY APPLICABLE TO TOTAL-
IZATORSJohn Handley, Purley, England, assignor to The
Union Totalisator Company Limited, Glasgow,
Scotland, a company of Great BritainApplication July 20, 1948, Serial No. 39,618
In Great Britain December 5, 1947

2 Claims. (Cl. 235—92)

1

This invention relates to an aggregator of the type in which escapement wheels are biased to rotate by slipping clutches or other means when released by electrically and mechanically operated escapement levers or pawls.

More particularly, the invention is concerned with improvements in devices of the type set forth in my prior patent application No. 723,532 dated January 22, 1947.

The present invention has for its object to enable the aggregator to operate at much higher speed than previously, without undue strain to the moving parts which are subjected to intermittent movements.

There are already known systems in which electromagnets are used for counting, by operating escapement pawls which release ratchet wheels whose movements are combined by differential gearing and urged by spring drive, but there is considerable inertia in the differential gears which limits the speed of counting, and throws heavy strain on the armatures of the electromagnets each time the drive is arrested.

In the present invention there is a light spiral spring associated with each escapement wheel, and the wheels are as light as possible, so that when an armature of an electromagnet operates, the wheel follows up instantly. The movements of, say, three escapement wheels are combined to a single driving arm by two differential gears, though it will be apparent that any desired number of escapement wheels may be employed. The driving arm is urged by a spring just heavy enough to overcome the thrust of the light springs in the three escapement wheels. This heavy spring is anchored at its other end to a driving gear, urged to rotate by a slipping clutch drive, and coupled to the general transmission of the aggregator.

The driving gear also carries a pawl which engages a fixed ratchet wheel when the driving arm is arrested, so that the thrust of the driving gear slipping clutch and the inertia of the general transmission of the aggregator will also be taken on the fixed ratchet wheel after each movement released by the escapement wheels. This ratchet wheel and the pawl carried by the driving gear are of robust section, but do not affect the counting speed by their inertia.

To protect them as far as possible, however, the ratchet wheel is loosely mounted on an adjustable boss, and the inside of the wheel and the outside of the boss each have a protruding tongue, these tongues being urged together by a heavy spring, so that the shock of arresting the driving gears is taken by the spring.

2

To release the pawl easily from the fixed ratchet wheel, the driving arm carries a roller, which nestles under the edge of the pawl, which overhangs the ratchet wheel at one side. Therefore when it is moved by the driving arm this roller lifts the pawl out of engagement with the minimum effort as soon as the arm starts to move in response to release on the escapement wheels.

10 An aggregating device according to the invention is illustrated in the accompanying drawings in which:

Fig. 1 shows a side view of an aggregator counting unit according to the present invention;

15 Fig. 2 is a left hand elevation of Fig. 1;

Fig. 3 is a sectional view of part of Fig. 1 with certain parts omitted; while

Fig. 4 is an end view derived from Fig. 3.

An aggregator according to the present invention is driven by a motor which drives it through a series of gears and shafts. Such an aggregator comprises three counting units and four transmission units for carrying out transfer to the next higher order of counting and for controlling an indicator.

25 A counting unit, that associated with the units portion of the complete aggregator will now be particularly described.

Referring particularly to Fig. 1, the counting unit has three relays 28, 29 and 30 adapted respectively to respond to impulses characteristic of one, two and five units.

30 Associated with the relay 28 is a ratchet wheel 34 which is a force-fit on a boss 99 (see Fig. 3). The boss 99 has a slot 37b in which is anchored the inner end of a spring 37a, the outer end of which is anchored to the spring casing 37. The spring casing 37 is bolted to a crown wheel 52, the first wheel in the gear train. Corresponding equipment associated with the relays 29 and 30 is generally similarly arranged.

35 Between the crown wheels 52 and 53 are placed two pinions 100 and 101 carried by a spider 54. The spider 54 is keyed to the shaft 55 (see Fig. 3) to the other end of which is keyed a spider 56 carrying pinions 49, 49a, placed between the wheels 48 and 50. Thus, two differential gear boxes are formed. The crown wheel 59 (the final wheel in the gear train) is carried on the extreme end of the shaft 51, which abuts against the end of the shaft 55.

40 It will be observed that the sleeve 50a keyed to the shaft 51 (to which the crown wheel 59 is bolted) has a portion of its bore adapted to receive the end of the shaft 55. The object of this is to ensure correct alignment of these shafts.

It should be noted that the ratchet wheel 36 (the five unit wheel) rotates in the opposite direction to the other two ratchet wheels, whereby additive summation onto the crown wheel 50 occurs. It will be understood that the numbers of teeth on the ratchet wheels are dependent on the number of units to be recorded thereby; thus, the ratchet wheel 36 has one fifth as many teeth as the wheel 34, so for one received impulse it revolves five times as far as does the wheel 34. Similarly, the wheel 35 has half as many teeth as the wheel 34.

The opposite end of the shaft 51 (Fig. 3) to that to which the wheel 50 is fixed, passes through a block 1 on which the driving gear 26 is freely mounted, and a fixed ratchet wheel 41. At its extreme end is mounted an arm 43. The driving gear 26 is driven by the electric motor through a gear train and slipping clutch in known manner. To one end of the arm 43 is attached a spring 42, the other end of which is anchored to the driving gear 26. Also mounted on the driving gear 26 is a pawl 40 held in engagement with a fixed ratchet wheel 41 by a spring 47. It will be observed that, in order to avoid confusion, the fixed ratchet 41 and the pawl 40 are not shown in Fig. 3. The spring 42 urges the shaft 51 to rotate in the direction of the arrow A (Fig. 4), but this cannot occur since the gear 26 (and hence the shaft 51) is held stationary by the pawl 40 engaging the fixed ratchet 41.

Also mounted on another leg of the arm 43 is a roller 44 adapted when the arm 43 rotates to lift the pawl 40 (whose toe overhangs the fixed wheel 41) and permit the driving gear 26 to be driven from the slip clutch and to move the arm 43 (and the shaft 51) until the roller 44 permits the pawl 40 to re-engage the ratchet 41.

The action of the counting unit will now be described with particular reference to the single unit relay 28.

When the relay 28 receives an impulse which is characteristic of one unit, it rocks its armature 31. The double-ended pawl 31a carried by this armature permits the ratchet wheel 34 to turn one tooth's distance under control of the spring 31a. Mounted on the spring casing 37 is a pin 45 which normally engages a pin 46 on the ratchet wheel 34. When the wheel 34 moves, these pins are therefore separated. The crown wheel 52 is therefore released by the escapement action of the ratchet wheel. Therefore, through the pinions 100 and 101, the shaft 55, the spider 56 and the pinions 49 and 49a, the crown wheel 50 is free to rotate. As this is attached to the shaft 51, the arm 43 is free to rotate, and does so under tension of the spring 42. This carries the roller 44 with it a sufficient distance to disengage the pawl 40 from the ratchet wheel 41. Therefore, the wheel 26 is freed and is driven round by the motor through the slip clutch drive and pulls the shaft 51 with it until the movement of the escapement wheel has been absorbed. When this occurs the pin 45 on the spring casing 37 engages the pin 46 on the wheel 34 which stops the ratchet wheel and through the gear train described above stops the shaft 51. The driving gear 26 "overruns" slightly, carrying the pawl 40 with it until its toe is just clear of the roller 44. The pawl 40 then re-engages the fixed ratchet wheel 41, stopping the wheel 26 and leaving the spring 42 in tension, whereby the unit is ready to record the next impulse. When the

pins 45 and 46 re-engage as the ratchet wheel 34 and the crown wheel 52 have resumed their initial position relative to one another, it is apparent that the spring 31a is re-tensioned.

It will be clear that operation of the aggregating equipment in response to reception of "two unit" and "five unit" impulses is generally similar to that for single unit impulses except that greater distances are moved by the wheels.

Simultaneous aggregation from two or three escapement wheels can also occur when necessary.

In order to prevent the arm 43 rotating too far when it first moves, a stop 42a on the wheel 26 is provided, so placed that the arm rotates a sufficient distance for the roller 44 to lift the pawl 40 before it reaches said stop.

On the inside of the ratchet wheel 41 is a tongue 51 (Fig. 2). The wheel 41 is located on a large boss 53 having a tongue 59. These two tongues are urged together by a C-shaped spring 60. This spring is capable of slight flexure so as to absorb the shock when the pawl 40 engages the ratchet wheel 41 at high speed.

The transfer mechanism and the transmission units of the aggregator are described in detail in my prior U. S. specification No. 723,532 of January 22, 1947.

What is claimed is:

1. An electromechanical aggregator adapted to respond to electrical impulses received at very high speed from a plurality of sources, comprising a plurality of spring-driven escapement wheels, means for applying said impulses to said spring-driven escapement wheels, a common shaft, a plurality of differential gears between said escapement wheels and said common shaft for aggregating the movement of said escapement wheels on to said common shaft, rotatable means co-axial with said common shaft, driving means for said rotatable means, a further spring-driven escapement device adapted to permit said rotatable means to rotate when said common shaft commences to move and to arrest the motion of said rotatable means when said rotatable means has moved a sufficient distance to absorb the motion of said common shaft, said further spring-driven escapement device comprising a fixed ratchet wheel, a pawl mounted on said rotatable means and adapted to engage said fixed ratchet wheel, and means responsive to motion of said common shaft to disengage said ratchet wheel and said pawl and to cause said pawl to engage said ratchet wheel to arrest the motion of said rotatable means.

2. An electromechanical aggregator as claimed in claim 1, in which said fixed ratchet wheel is provided with a shock-absorbing device adapted to take the shock of arresting transmission when engaged by said pawl.

JOHN HANDLEY.
